UNITED STATES PATENT OFFICE.

JOHN S. MOORE, OF SPRINGFIELD, MISSOURI.

DESIGN FOR A SIGNAL BOX.

Application filed June 28, 1927. Serial No. 22,588. Term of patent 7 years.

To the Commissioner of Patents:

Be it known that I, JOHN S. MOORE, a citizen of the United States, and a resident of Springfield, in the county of Greene and State of Missouri, have invented a new, original, and ornamental Design for a Signal Box, of which the following is a specification, reference being had to the accompanying drawing, forming part thereof.

Figure 1 is a side elevation of a signal box, showing my new design.

Figure 2 is a top plan view of a signal box, showing my new design.

I claim:

The ornamental design for a signal box, as shown.

JOHN S. MOORE.
